UNITED STATES PATENT OFFICE.

GEORGE N. TAYLOR, OF EAST PROVIDENCE, RHODE ISLAND, ASSIGNOR, BY MESNE ASSIGNMENTS, TO THE NEW ENGLAND TRUST COMPANY, TRUSTEE, A CORPORATION OF MASSACHUSETTS.

WINDING MACHINE.

Application filed July 16, 1921. Serial No. 485,278.

To all whom it may concern:

Be it known that I, GEORGE N. TAYLOR, of East Providence, in the county of Providence, State of Rhode Island, a citizen of the United States, have invented certain new and useful Improvements in Winding Machines, of which the following is a specification.

This invention relates to improvements in winding machines and particularly to winders of the friction- or drum-driven type.

The essential purpose of the invention is to provide improved means for controlling the action of the cop- or cone-holder in its movement away from the friction-roll or driving-drum during the growth of the package being wound on said holder.

One object of the improvement is to provide positively acting means for causing the cone-holder to travel in a predetermined path whereby its base end will move away from the drive-roll at a faster rate than that of its apex end, thus tending to cause the axis of the holder to assume a greater inclination to the periphery of the drive-roll whereby to increase the taper of the conical surface of the package being wound.

Another object of the improvement is to provide means for controlling the position of the cone-holder longitudinally of the drive-roll during its receding movement therefrom, whereby to cause the layers of winding on the cone to be disposed in proper relation to build the package with a convexed base and a concaved nose or apex end.

Another object of the improvement is to provide means for resisting the movement of the cone-holder away from the drive-roll to effect an even pressure of the surface of the cone thereagainst.

Another object of the improvement is to provide a dogging-device for checking the return of the cone-holder toward the drive-roll during the winding operation whereby to eliminate the jumping or vibration of the cone caused by irregularities on its surface.

Further objects of the improvement are set forth in the following specification which describes a preferred embodiment of the invention as illustrated in the accompanying drawings. In the drawings:

Fig. 1 is a front elevation of the essential elements of a winding machine showing the cone-holder on which the package is

wound, the friction-drum or drive-roll for rotating the cone, the thread-guide for traversing the yarn longitudinally of the cone-holder, and my improved means for controlling the movement of the cone-holder away from the drive-roll during the building up of the package thereon;

Fig. 2, a similar view showing the cone-holder in its raised position in relation to the drive-roll, which position it assumes at the completion of the cone;

Fig. 3, a plan view of the cone-holder and drive-roll, showing the controlling-means for the holder partly in section; and

Figs. 4 and 5, detail views showing the dogging-device which checks the movement of the cone-holder toward the drive-roll during the winding of the package.

Referring to Figs. 1, 2 and 3 of the drawings, D designates the cylindrical drive-roll or friction-drum from which the cop or package is rotated and usually the roll is driven continuously from a horizontal shaft 2 on which it is mounted. Arranged at the front of the drive-roll D is the usual thread-guide G which is carried by a reciprocating rod or traverse-bar 3 whereby it may be oscillated back and forth longitudinally of the axis of the drive-roll to adapt it to lay the yarn in helical coils on the package being wound. The driving connections for the drive-roll D and thread-guide G are not herein shown and described in detail since they may be of any usual arrangement as well known to those versed in the art.

It is the usual practice to wind the cone or package on a relatively thin paper tube or shell C, shown in Fig. 1, and the means for rotatively mounting the tube may consist of any suitable type of holder therefor. As here illustrated the cone-holder H comprises a mandrel 4 having conical end-pieces 5 and 6 adapted for insertion into the cone-tube C and provided with teeth, dogs or other suitable means, not herein shown, for securing the tube in place thereon. The mandrel 4 is rotatively mounted on a spindle 7 which is held at one end in a support or hinge-member 8 pivoted in a slot at the end of an arm 9. The member 8 is pivoted on a stud 10 to adapt it to be operated manually to swing the mandrel 4 outwardly away from the drive-roll D to facilitate the placing of the cone-tube C thereon.

and the doffing of the package therefrom. At the outer end of the member 8 is a notch 11 adapted to be engaged by a detent or catch 12 on the end of a spring 13 which is secured to the side of the arm 9 by means of screws 14 and nuts 15. The detent 12 serves to hold the mandrel 4 in operative position with its axis in line with that of the drive-roll D, while permitting the swinging action of the mandrel in placing the cop-tube thereon or removing it therefrom. The arm 9 carrying the mandrel 4 is fixedly supported at the outer end of a second arm 20 which controls the movement of the cone-holder and the cop or package wound thereon. As shown in Fig. 3, the arm 9 is mounted on a rod 21 and fixedly secured thereto by the screws 14 which fasten the spring 13 in place. The rod 21 is driven into a hub 22 at the end of the arm 20 and projects substantially at right angles thereto.

Referring now to Figs. 1 and 2, the opposite end of the arm 20 is formed with a sort of T-head comprising two opposite extensions 23 and 24 carrying rollers 25 and 26 which are pivoted on studs 27 driven into bosses at the extremities of the extensions, see also Fig. 3. The rollers 25 and 26 engage curved grooves or guideways 29 and 30 formed on the face of a vertical standard or plate 31 which is rigidly supported from a rod R forming a part of the framework of the winding machine, see Fig. 3. The arm 20 is held in position with its rollers 25 and 26 engaging the grooves 29 and 30 by means of a front cover-plate 32 fastened to bosses 33 on the standard 31 by screws 34, see Fig. 3. On the rearward side of the arm 20 is a finished face 35 which slides against the face of a machined rib 36 projecting forwardly from the standard 31. Fastened to the front of the arm 20 by means of a screw 37 is a flat spring 38 having a convexly formed button 40 at its outer end which is adapted to bear against the rearward face of the cover-plate 32. The tension of the spring 38 maintains the arm 20 bearing against the rib or track 36 on the standard 31 while providing a slight friction to resist the upward movement of the arm as its rollers 25 and 26 travel in the curved grooves or guideways 29 and 30. It will be noted by reference to Figs. 1 and 2 that the slots or guideways 29 and 30 are curved in opposite directions and are offset, one in relation to the other. This provides that as the rollers 25 and 26 travel in their respective slots the latter will act as cams to tilt or rock the arm 20 during its upward movement, whereby to shift the cone-holder H bodily in angular relation to the drive-roll D in the manner and for the purpose as hereinafter more fully explained.

As the cone-holder H swings upwardly from the drive-roll D its retrograde movement is checked by a dogging-device which

is constructed and arranged as next described. Surrounding the rod 21 which supports the cone-holder arm 9 is a hub 42 which is secured fixedly in place by a set-screw 43, see Figs. 3 and 4. On the side of the hub 42 is an arcuate quadrant 44 constructed integral therewith and formed with ratchet-teeth 45 on its concaved face. Adapted to engage with the teeth 45 on the quadrant 44 is a hooked pawl 46 which is pivotally mounted on an arm 47 projecting from a hub 48. As shown in Fig. 5, the hub 48 is provided with an axial stud 49 journaled in a bearing 50 projecting from the side of an upright plate or standard 51 which forms a part of the machine frame, see Figs. 1 and 2. Referring again to Figs. 4 and 5, the arm 47 is of bifurcated construction to adapt the quadrant 44 to pass between its opposite sides. The pawl 46 has a hub 52 pivoted between the sides of the arm 47 by means of a pin 53 driven through the arm and engaging a vertical slot 54 at the lower end of the pawl, see Fig. 4. The slot 54 permits the pawl 46 to rock on its pivot and also to move up and down to a limited extent in the manner and for the purpose as hereinafter more fully explained. The pawl 46 is normally maintained in its raised position by means of a flat spring 55 which bears against a rounded toe 56 at its lower end. The spring 55 is fastened to the under side of the hub of the arm 47 by a screw 57, see Fig. 4. Projecting from the side of the pawl 46 is a pin 58 adapted to strike against a finger or stop 59 on the side of the arm 47 to limit the rocking movement of the pawl. The hub 48 of the arm 47 is extended outwardly as shown in Fig. 5 and bored to receive a rod 60 arranged coaxially with the bearing-stud 49 at its opposite end. The rod 60 is fastened in the bore of the hub 48 by means of a set-screw 61. The rod 60 is bent at an angle at its outer end to adapt it to serve as a handle 62 for rocking the arm 47 to release the pawl 46 from the teeth on the quadrant 44. The rod 60 may also be connected to operate the starting and stopping mechanism of the machine, but as these connections are not essential to the present invention they are not herein shown or described. Suffice it to state that the rod 60 is rocked in the direction indicated by the arrow α in Fig. 2 to start the machine, and in the opposite direction to arrest its operation.

Referring to Figs. 4 and 5, the bearing-stud 49 for the pawl-carrying arm 47 carries a vertical arm 64 secured to its inner end, and hooked into a hole at the upper extremity of said arm is a coiled spring 65 having its opposite end anchored to a pin 66 driven into a boss on the fixed standard 51. The spring 65 tends to rock the arm 47 and its starting-handle 62 in the direction β

opposite to that indicated by the arrow α in Figs. 2 and 4. When the machine is set for operation the arm 47 is maintained in the position illustrated in Fig. 4 and held 5 against the tension of the spring 65 by a detent-mechanism arranged as next described. Referring to Fig. 5, the rod 60 which projects from the hub 48 of the arm 47 carries a detent-lever 67 fastened thereto by a set- 10 screw 68 in its hub. The lever 67 extends downwardly and outwardly, see also Fig. 4, to adapt its lower squared end to engage with a shoulder or notch 69 in the side of a detent-member or latch-plate 70. The 15 latch-plate 70 may be operated by suitable instrumentalities, not herein shown, to release the lever 67 to allow the rod 60 to be rocked from the spring 65 to cause the automatic stopping of the machine in the manner as usually arranged in apparatus of the 20 present type.

The structure and arrangement of the essential elements of my improved mechanism having now been described in detail its 25 method of operation will next be explained: To prepare the machine for operation the mandrel 4 is swung outwardly on its pivot 10 and the cop-tube C applied thereto; after which the mandrel is swung back to the 30 position illustrated in Fig. 3, where it is held in operative relation by the detent 12 engaging the notch 11 in the hinge-member 8. The thread or yarn y , represented by dash lines in Fig. 3, is drawn up from its 35 source of supply, not herein illustrated, threaded through the groove in the thread-guide G, and its end secured to the tube C by giving it a few turns therearound. To start the machine the controlling-handle 62 40 is rocked in the direction indicated by the arrow α in Fig. 2 against the tension of the spring 65. This action causes the winding operation to be started by moving the cop-holder H down against the drive-roll D, and to maintain the machine operative 45 the latch-member 70 engages automatically with the end of the detent-lever 67 in the manner illustrated in Fig. 5. In turning the handle 62 to start the operation of the 50 machine the arm 47 is rocked in the same direction and to a sufficient extent to cause it to release the pawl 46 from the quadrant 44. This action is effected by the engagement of the finger or stop 59 on the arm 47 55 with the pin 58 on the side of the pawl, see Fig. 4. Upon the release of the pawl 46 from the quadrant 44 the weight of the cop-holder H will cause the latter to drop to bring the cop-tube C into contact with the 60 periphery of the drive-roll D. As the cop-tube C is thus brought down against the drive-roll D the frictional contact between their peripheral surfaces will cause the tube and its mandrel 4 to be rotated to wind on 65 the yarn y as it feeds through the thread-

guide G. Meanwhile, the thread-guide G is reciprocated back and forth along the tube C to traverse the yarn y longitudinally thereof, whereby it is deposited on the tube in helical coils to build up a cross-wound 70 package in the manner as well known to those versed in the art. As the yarn is built up on the tube C it will cause the mandrel 4 to rise away from the drive-roll D and the lifting action of the mandrel is 75 controlled by the action of the movable arm 20 connected to its end. In winding packages of the present type, that is conical cops, it has been found expedient to start 80 the winding with a predetermined taper and to gradually increase the taper or pitch of the cone as the latter grows in diameter. Usually the conical core or cop-tube C on which the package is wound has a predetermined taper which is of the maximum pitch 85 on which it is practical to hold the first coils of winding without slippage. As the package increases in diameter, however, the windings have a better foundation so that the layers may be inclined at a greater angle to the axis of the cone without danger 90 of slippage. It is desirable to have the outer layers of the cone inclined to a greater extent than the inner ones in order to insure freedom of delivery of the yarn in 95 unwinding the cone, and hence it has become the preferred practice to start the winding with the minimum taper and to gradually increase the inclination or taper on the surface of the cone as the latter increases in diameter. To provide for this 100 increase in the taper of the cone during its building various methods of laying the yarn thereon have been employed. One preferred system for building up the yarn faster at 105 the base of the cone than at its apex end to increase its taper is to cause the thread-guide to lay the coils or turns of the yarn in closer relation toward the larger end 110 of the cop-tube. That is to say, the thread-guide G is given a variable motion in its traverse along the cone-holder H, its speed of reciprocation being accelerated toward the apex end of the cone and decelerated in the opposite direction. The means for 115 effecting this peculiar action of the thread-guide are not herein shown or described since they are disclosed in my U. S. Patent No. 1,427,035, granted August 22, 1922. Suffice it to state that in the present machine the cone or package X, represented by 120 dot-and-dash lines in Fig. 2, is built up faster at its base than at its apex end and consequently the cone-holder or mandrel 4 must be gradually tilted to bring its axis to a greater inclination to the face of the 125 drive-roll D. This tilting action of the mandrel 4 is controlled from the arm 20 through the action of the guideways or cam-grooves 29 and 30 on the rollers 25 and 26. 130

It will be noted from Figs. 1 and 2 that as the outer end of the arm 20 is forced upwardly under the rising action of the cone-holder H the upper roller 25 will travel in a curved path defined by the groove 29 which has a general inclination to the right; while the lower roller 26 traveling in the groove 30 follows a curved path inclined in the opposite direction, or to the left. The curve and inclination of these grooves are plotted to give a certain definite path of movement to the mandrel 4 as next explained. In a general sense the point of connection of the mandrel 4 with the arm 20, represented at *a* in Fig. 1 and at *b* in Fig. 2, swings in a path defined by the broken line *a*—*b* in Fig. 2. This path is not a true arc but follows a reverse curve generated by the point *a* swung from a pivot located to the right a distance approximately four or five times the length of the package, with said pivot moving constantly to the left in a horizontal plane. The purpose of this peculiar action of the arm 20 to move its point of connection with the cone-holder H in the path as indicated is to effect the proper tilting action of the mandrel 4 while controlling its position longitudinally of the drive-roll D. It is obvious that if the cone-holder were swung upwardly on an arc inscribed from a center defined by the intersection of its axis with the face of the drive-roll D then its rising movement would cause the mandrel 4 to be shifted to the right to a considerable extent in relation to the position of the drive-roll D and the path of traverse of the thread-guide G. Such a direction of movement of the mandrel would result in building the base and apex ends of the cone substantially perpendicular to the surface of the tube C or, in other words, the ends of the cone would be formed substantially flat. In order to provide for greater stability of the winding and also to prevent overruns or "cobwebs" on the base of the cone it is of advantage to form the base slightly convexed. It will be observed from Fig. 2 of the drawings that as the cone-holder H travels in the plotted path *a*—*b* the mandrel 4 will be maintained in a predetermined position in longitudinal relation to the drive-roll D whereby to cause the cone to be built with the proper degree of convexity on its base. Stated briefly, the movement of the cone-holder H away from the drive-roll D is controlled by the arm 20 and its correlated mechanism to allow the mandrel 4 to tilt in proportion to the increase in taper on the surface of the cone being wound without causing the cone to be displaced in such manner as to tend to build its base too flat. Furthermore, the positive connection of the cone-holder H with the arm 20 insures that the cone shall be maintained constantly in position with

its axis in a vertical plane coincident with the axis of the drive-roll D whereby to prevent it from assuming a "skewed" relation thereto. This latter provision is important as insuring a full contact of the cone with the drive-roll along its whole length. It will thus be seen that the relation of the cone-holder H to the drive-roll D is controlled positively and definitely throughout the whole winding operation and in this way the shape of the cone is regulated within predetermined limits whereby to secure a more uniform product of superior quality. This improved means for positively and automatically controlling the movement of the cone-holder during the building of the package is believed to be broadly novel in the art.

As a further means for controlling the action of the cone-holder H to check its retrogressive movement toward the drive-roll D I have provided the improved dogging-device, which functions as follows: In starting the machine to operate in the manner as before explained the rocking of the handle 62 tilts the arm 47 into position to allow the pawl 46 to engage with the teeth 45 on the quadrant 44, this action being effected by the pressure of the spring 55 on the lower toe 56 of the pawl. When, therefore, the quadrant 44 is carried upward with the arm 9, to which it is attached, the pawl 46 will ride over the teeth 45 and engage individually therewith to check the downward movement of the cone-holder H. It frequently happens that the cone-tubes C are not perfectly concentric so that they run out of true when in contact with the periphery of the drive-roll D. Likewise, the surface of the cone itself may have lumps or high spots and such irregularities tend to lift the cone off from the drive-roll with a jumping or vibrating action which prevents a uniform driving contact and thus causes imperfect winding. For instance, if the cone were lifted to such an extent that the pawl 46 skipped a tooth on the quadrant 44 the cone-holder might be held with the surface of the cone out of contact with the drive-roll except at the high point on the cone and consequently the driving action of the roll would become irregular. Such abnormal functioning of the apparatus tends to cause faults in the winding which are apt to be exaggerated as more yarn is wound on to the cone. To guard against such conditions I have provided for an inductive release of the checking-action of the pawl 46 as next explained. As before described, the pawl 46 is pivoted to the arm 47 in such manner as to permit it to rise and fall slightly under the control of the spring 55. Therefore, when the cone jumps away from the drive-roll to such an extent that the pawl 46 skips a tooth on the quadrant 44, immediately this jumping action is over-

come the weight of the cone-holder acts to force the pawl 46 downward against the pressure of its spring 55. This relief-action of the pawl is provided for by its slot 54 which allows it to slide up and down on the pivot pin 53; but as soon as the cone begins to rise again under its normal growth in diameter the vertical play of the pawl will be taken up by the spring 55 to force the pawl 10 back to its normal position, as illustrated in Fig. 4. It will thus be seen that through this automatic relief-action of the pawl 46 the cone-holder H is controlled in its movement to insure a smoother, more uniform 15 driving action of the drive-roll D and consequently the winding operation is rendered more uniform and the character of the product materially improved.

The operation of the machine is arrested 20 automatically, upon the breakage of the yarn or the completion of the package, through the employment of stopping-means of any suitable arrangement. This part of the apparatus forms no part of the present 25 invention, however, and is therefore not herein shown or described; but it is to be noted that when the detent-lever 67 is released from the notched latch-plate 70 the spring 65 will act to rock the arm 47 to raise 30 the pawl 46 bodily and the engagement of the pawl with the quadrant 44 will cause the latter to be forced upwardly to lift the package away from the drive-roll D to arrest its rotation.

35 Various modifications may be made in the structure and arrangement of the parts of my improved apparatus without departing from the spirit or scope of the invention; therefore, without limiting myself to the 40 act embodiment herein shown and described, I claim:

1. In a winding machine, the combination 45 of a drive-roll, a cop-holder for supporting the cop in contact with the drive-roll, and means for positively controlling the position 50 of the cop-holder in its movement away from the drive-roll during the growth in the winding to rigidly hold said cop-holder in certain predetermined angular relation to the drive-roll in all positions of its movement.

2. In a winding machine, the combination 55 of a drive-roll, a cop-holder for supporting the cop in contact with the drive-roll, means for mounting the cop-holder to adapt it to move away from the drive-roll during the growth in the winding, and means for positively defining the path of movement of the cop-holder while rigidly holding it in certain predetermined inclined relation to the 60 drive-roll in all positions of its movement away from said drive-roll.

3. In a winding machine, the combination 65 of a drive-roll, a cop-holder for supporting the cop in contact with the drive-roll, means

for supporting the cop-holder to adapt it to move away from the drive-roll during the growth in the winding, and means acting on said supporting-means to cause the cop-holder to move in a curved path generated 70 from a pivot which is progressively displaced longitudinally of the axis of the drive-roll.

4. In a winding machine, the combination 75 of a drive-roll, a cop-holder for supporting the cop in contact with the drive-roll, means for supporting the cop-holder to adapt it to recede from the drive-roll, and means acting on said supporting-means to cause it to positively tilt the cop-holder to incline its 80 axis to a predetermined extent in relation to the drive-roll during its movement therefrom while preventing the cop-holder from rocking with respect to the drive-roll.

5. In a winding machine, the combination 85 of a drive-roll, a cop-holder for supporting the cop in contact with the drive-roll, and means acting on the cop-holder to positively and continuously tilt the latter to a predetermined inclination in relation to the drive-roll during its movement therefrom while holding it from rocking with respect to the 90 drive-roll.

6. In a winding machine, the combination 95 of a rotatable cop-holder, a drive-roll for rotating the cop wound on the holder, and means for controlling the movement of the cop-holder away from the drive-roll during the growth of the cop to effect a positive tilting action of the holder to incline its axis 100 in predetermined relation to the drive-roll without permitting it to rock with respect to the drive-roll.

7. In a winding machine, the combination 105 of a rotatable cop-holder, a drive-roll for rotating the cop wound on the holder, and means for guiding the cop-holder in its movement away from the drive-roll during the growth of the cop whereby to positively tilt the cop-holder to effect a gradually increasing inclination of its axis in relation to the drive-roll without allowing the cop-holder to rock with respect to the drive-roll.

8. In a winding machine, the combination 110 of a rotatable cop-holder, a drive-roll for rotating the cop wound on the holder, means for supporting the cop to adapt it to recede from the drive-roll during the growth in the winding, and means acting on said supporting-means to cause a gradually increasing 120 inclination of the cop-holder in relation to the drive-roll during its movement therefrom without allowing the cop-holder to rock with respect to the drive-roll.

9. In a winding machine, the combination 125 of a rotatable cop-holder, a drive-roll for rotating the cop wound on the holder, means for supporting the cop-holder to adapt it to recede from the drive-roll during the growth 130 in the winding, and means for regulating

- the path of movement of the cop-holder to control its longitudinal relation to the drive-roll while causing it to assume a gradually increasing inclination with respect thereto, said last named means acting to hold the cop-holder rigidly to prevent it from rocking with respect to the drive-roll.
10. In a winding machine, the combination of a rotatable cop-holder, a friction drive-roll, means for supporting the cop-holder to adapt it to recede from the drive-roll during the growth in the winding, and means operating on said supporting-means with a cam-action to effect a gradually increasing inclination of the cone with respect to the drive-roll during its movement therefrom without allowing the cop-holder to rock toward or away from the drive-roll.
11. In a winding machine, the combination of a rotatable cop-holder, a friction drive-roll, a guideway, and means traveling in said guideway and acting on the cop-holder to cause the latter to move away from the drive-roll in a predetermined path with its axis progressively inclined to the face of the drive-roll, said guideway acting to positively hold the cop-holder against rocking motion with respect to the drive-roll.
12. In a winding machine, the combination of a rotatable cop-holder, a friction drive-roll, means for supporting the cop-holder to adapt it to recede from the drive-roll, a cam-shaped guideway, and means traveling in the guideway to define the path of movement of the cop-holder while holding the latter in certain predetermined inclined relation to the drive-roll without allowing it to rock with respect thereto.
13. In a winding machine, the combination of a rotatable cop-holder, a friction drive-roll, a guideway, means for supporting the cop-holder, and rollers on said supporting-means adapted to travel along the guideway to control the path of movement of the cop-holder with respect to the drive-roll.
14. In a winding machine, the combination of a rotatable cop-holder, a friction drive-roll, an arm attached to said cop-holder, rollers on said arm, and a guideway along which said rollers travel during the movement of the cop-holder away from the drive-roll to control the position of the cop-holder with respect to the drive-roll.
15. In a winding machine, the combination of a drive-roll, a cam-shaped guideway, a support slidable on the guideway, and a cop-holder rotatably mounted on the support, said guideway acting to determine the path of movement of the cop-holder with respect to the drive-roll.
16. In a winding machine, the combination of a drive-roll, a cam-shaped guideway, a support, rollers on said support adapted to travel on the guideway, and a cop-holder ro-
- tatably mounted on the support, said guideway acting to control the position of the cop-holder in relation to the drive-roll.
17. In a winding machine, the combination of a drive-roll, a guideway having oppositely-inclined guiding grooves, a support, means on said support travelable in the guiding grooves, and a cop-holder rotatably mounted on the support to adapt it to move therewith under the control of the guiding grooves to regulate the position of the cop-holder with respect to the drive-roll.
18. In a winding machine, the combination of a drive-roll, a fixed standard having cam-shaped guideways, a support, means on said support travelable in the guideways, a spindle carried by the support, and a cop-holder rotatably mounted on the spindle and movable with the support whereby the relation of the spindle with respect to the drive-roll is determined by the guideways.
19. In a winding machine, the combination of a drive-roll, a fixed standard having oppositely - inclined - curved guideways, an arm, rollers on said arm adapted to travel in the guideways, and a cop-holder rotatably mounted on the arm and movable therewith to define its path of movement under the action of the guideways.
20. In a winding machine, the combination of a drive-roll, a standard having guideways, a support, means on said support slidable in the guideways, friction means for resisting the movement of the support on the standard, and a rotatable cop-holder carried by the support with its path of movement defined by the guideways.
21. In a winding machine, the combination of a drive-roll, a standard, a support slidable on the standard, a cop-holder carried by the support, and a spring on said support adapted to bear against a part of the standard to resist the sliding movement of the support as it travels on the standard to direct the cop-holder in its movement away from the drive-roll.
22. In a winding machine, the combination of a fixed standard, a cover-plate secured to said standard, a support slidable between the standard and its cover-plate, a cop-holder carried by the support, and a spring on the support bearing against the cover-plate to resist the sliding movement of the support as it slides on the standard to control the movement of the cop-holder with respect to the drive-roll.
23. In a winding machine, the combination of a drive-roll, a cop-holder adapted to recede from the drive-roll during the growth of the cop, a ratchet, a pawl engaging said ratchet to resist the movement of the cop-holder toward the drive-roll, and resilient means for maintaining the pawl in engagement with the ratchet while allowing the pawl to yield when so engaged whereby to

permit a slight movement of the cop-holder toward the drive-roll.

24. In a winding machine, the combination of a drive-roll, a cop-holder adapted to recede from the drive-roll during the growth of the cop, dogging-means for checking the movement of the cop-holder toward the drive-roll, and resilient means acting through the dogging-means to provide a relief of the dogging action whereby to permit a slight movement of the cop-holder toward the drive-roll.
25. In a winding machine, the combination of a drive-roll, a cop-holder adapted to recede from the drive-roll during the growth of the cop, a ratchet, a pawl engaging said ratchet to resist the movement of the cop-holder toward the drive-roll, and a resilient mounting for the pawl adapted to permit a slight play of the ratchet while the pawl is engaged therewith.

26. In a winding machine, the combination of a drive-roll, a cop-holder adapted to recede from the drive-roll during the growth of the cop, a ratchet moving with the cop-holder, a pawl pivoted to engage the ratchet and adapted to slide on its pivot, and a spring for maintaining the pawl in engagement with the ratchet while permitting it to yield slightly under the weight of the cop-holder. 25

27. In a winding machine, the combination of a drive-roll, a cop-holder adapted to recede from the drive-roll during the growth of the cop, a ratchet, a pawl, a pin and slot 35 mounting for the pawl, and a spring for holding the pawl in engagement with the ratchet while allowing it to yield slightly on its mounting.

In testimony whereof I affix my signature.

GEORGE N. TAYLOR.
